(57) **CLAIM**

The ornamental design for a water bottle organizer as shown and described.

DESCRIPTION

FIG. 1 is a perspective view of a water bottle organizer, showing the first embodiment of my new design in an extended state;

FIG. 2 is the second perspective view thereof;

FIG. 3 is the third perspective view thereof;

FIG. 4 is a front elevational view thereof, the rear elevational view being a mirror image of FIG. 4;

FIG. 5 is a left elevational view thereof, the right elevational view is identical;

FIG. 6 is a top plan view thereof;

FIG. 7 is a bottom plan view thereof;

FIG. 8 is a partial enlarged view of FIG. 3;

FIG. 9 is a partial enlarged view of FIG. 3;

FIG. 10 is a partial enlarged view of FIG. 3;

FIG. 11 is a partial enlarged view of FIG. 3;

FIG. 12 is a partial enlarged view of FIG. 3;

FIG. 13 is a perspective view of the water bottle organizer in a contracted state;

FIG. 14 is a perspective view of a water bottle organizer, showing the second embodiment of my new design in an extended state;

FIG. 15 is the second perspective view thereof;

FIG. 16 is the third perspective view thereof;

FIG. 17 is a front elevational view thereof, the rear elevational view being a mirror image of FIG. 17;

FIG. 18 is a left elevational view thereof, the right elevational view is identical;

FIG. 19 is a top plan view thereof;

FIG. 20 is a bottom plan view thereof;

FIG. 21 is a partial enlarged view of FIG. 16;

FIG. 22 is a partial enlarged view of FIG. 16;

FIG. 23 is a partial enlarged view of FIG. 16;

FIG. 24 is a partial enlarged view of FIG. 16;

FIG. 25 is a partial enlarged view of FIG. 16; and,

FIG. 26 is a perspective view of the water bottle organizer in a contracted state.

The broken lines are for illustrative purposes only and form no part of the claimed design.
